UNITED STATES PATENT OFFICE.

GEORGE P. TILTON, OF NEWBURYPORT, MASSACHUSETTS, ASSIGNOR TO THE
TOWLE MANUFACTURING COMPANY, OF SAME PLACE.

DESIGN FOR A SPOON.

SPECIFICATION forming part of Design No. 20,731, dated May 19, 1891.

Application filed April 18, 1891. Serial No. 389,507. Term of patent 7 years.

To all whom it may concern:

Be it known that I, GEORGE P. TILTON, of Newburyport, in the county of Essex and State of Massachusetts, have invented a Design for Spoons, of which the following is a full, clear, and exact description.

Reference is to be had to the accompanying drawing, forming a part of this specification, in which the figure represents a face view of a spoon embodying my design.

For my present design I have devised and adopted ornamentation commemorative or remindful of the throwing overboard of tea by the colonists of Boston.

The leading feature of my design consists of a male figure attired in Indian costume and appearing as if engaged in emptying a box of tea into the water.

The letter *a* indicates the said male figure, and *b* the representation of a tea-box, the said figures being represented at the side of a vessel. The minor figures of the handle orna-

mentation include the representation of water in the foreground (indicated by the letter *c*) and the representation of a ship in the background, (indicated by the letter *d*.) On the bowl of the spoon appears the representation of Faneuil Hall, (indicated by the letter *e*.) On the handle of the spoon appear the word "Boston" and the numerals "1773," and on the bowl appears the name "Faneuil Hall;" but such words and numerals and the representation of the building are non-essential, the main feature of the design being the scene representing the historic incident of the throwing overboard of tea.

I claim—

The design for spoons herein shown and described.

GEO. P. TILTON.
